DRINKING CUP

Application filed June 5, 1928. Serial No. 282,947.

This invention is a foldable paper drinking cup having a trough-like pouring extension, of a type somewhat similar to the cup shown in the patent to Philip A. Fischer 5 1,558,602 dated October 27, 1925.

One of the important considerations in drinking cups of the type which fold flat is to provide a cup which will open easily, preferably simply by the user pressing together the sides of the cup. One of the 10 important objects of this invention is to provide a cup which may be readily opened.

Another important feature of this cup is that it is provided with a trough-like pouring 15 extension at one end, which is reenforced by flaps which are bent around onto the back of the extension, thereby leaving the top or pouring side of the extension entirely smooth and unobstructed.

20 The described flaps are bent or folded onto the back of the pouring extension along converging lines, such that small, substantially triangular portions of the front of the cup are carried around to the back of the 25 cup. This particular construction aids in defining the trough-like pouring extension and facilitates the opening of the cup.

The tip edge of the pouring extension may also be bent back and secured to the back of 30 the pouring extension, thereby stiffening it and leaving a smooth edge.

Other advantages and details of construction will be described in connection with the accompanying drawings, illustrating several 35 embodiments of the invention. It should be understood that the disclosure here is illustrative and not restrictive of the invention, and that it may be carried out in other ways, as expressed within the scope of the claims.

40 In the drawings:

Fig. 1 is a front view of the cup in a preliminary stage of making it;

Fig. 2 is a similar view showing the next stage;

45 Fig. 3 is a similar view showing the completed cup;

Fig. 4 is a perspective view of the completed cup;

50 Figs. 5 and 6 show a modification, Fig. 5 showing the parts before they are pasted

in final position and Fig. 6 showing the completed cup;

Figs. 7 and 8 show another modification, Fig. 7 showing the parts before being pasted in final position and Fig. 8 showing the completed cup;

Figs. 9 and 10 show another modification, Fig. 9 showing the parts before being pasted in final position and Fig. 10 showing the completed cup.

Fig. 11 is an end view of the cup when provided with creases.

Referring now to these drawings in which similar reference characters represent similar parts, the cup comprises a front portion composed of overlapping flaps 2 and 4 and an upwardly turned bottom flap 6, pasted as usual for forming the body of the cup. 8 indicates the back of the cup. The top edges 10 and 12 of the front portions 2 and 4 are 70 curved upwardly as shown in Fig. 1.

The back 8 of the cup is extended to form a tapered pouring extension 14 and a pair of flaps 16 and 18 integral with the pouring extension, the pouring extension being defined by the converging lines of fold 20 and 22.

With the parts as shown in Fig. 1, the flaps 16 and 18 are folded outwardly and backwardly onto the back of the pouring extension, as shown in Fig. 2, into overlapping relation, as shown at 24, the flaps being pasted to each other and to the back of the cup.

Referring to Fig. 1 it will be noted that 85 the lines of fold 20 and 22 define small substantially triangular portions 26 and 28, these triangular portions being part of the front portions 2 and 4 of the cup. When the flaps 16 and 18 are carried around to the back of 90 the cup as has been described, these triangular portions are carried with the flaps around to the back of the cup.

After the two flaps are thus secured to the back of the pouring extension, the tip of 95 the pouring extension, indicated at 30, Fig. 2, is bent outwardly and backwardly on the line 32 onto the back of the cup and pasted there, as shown in Fig. 3, thereby completing the cup.

Referring to Fig. 4, it will be seen that when the cup is in use, the pouring extension 14 is entirely smooth on its pouring side, since the flaps are on the other side. The edges 5 20 and 22 of the pouring extension slope sharply upwardly to points P, P which are well within the lateral edges of the cup, thereby making a deeper and narrower trough, whereby the liquid will not be spilled over the sides of the pouring extension 14, even though the cup is tilted sharply. With the 10 described construction, the cup may be very readily opened for filling.

Referring now to the modifications shown 15 in Figs. 5 and 6, the front portions 2 and 4 of the cup cooperate with the back 8 as before, the back 8 being extended to form a pouring extension 30 and flaps 32 and 34. These flaps are folded outwardly and backwardly along converging lines 36 and 38 onto the back of the cup as shown in Fig. 6 and pasted to the back of the cup. This folding of the flaps carries small triangular portions 40 and 42 of the front of the cup around 20 to the back of the cup in the same way as described in connection with Fig. 1. The tip edge 44 of the pouring extension is folded outwardly and backwardly on the line 46 and pasted to the back of the cup, over the two 25 flaps 32 and 34, thereby giving a pouring edge which is smooth and sufficiently rigid.

Referring now to Figs. 7 and 8, the front portions 50 and 52 are respectively provided with triangular projections 54 and 56. In 30 this form no flaps are used, the back of the cup being cut along the converging lines 58 to form a tapered pouring extension 60, the pouring edge of which is indicated at 62. The small triangular portions 54 and 56 are 35 bent outwardly and backwardly onto the back of the pouring extension 60 and pasted there, as shown in Fig. 8, thereby completing the cup.

Referring now to Figs. 9 and 10, the cup 40 comprises overlapping front portions 64 and 66 and a bottom flap 68. The front portions 64 and 66 converge toward the mouth of the cup, as shown. The upper edges of the front portions are curved as shown at 70. The back 50 of the cup is extended to form the pouring extension 72 and flaps 74 and 76, which are folded outwardly and backwardly along converging lines 78 and 80 onto the back of the cup and pasted there. This folding of the flaps carries small triangular portions 82 and 84 from the front of the cup around to the back of the cup, as described in connection with the other forms. The tip 86 of the pouring extension is bent backwardly and outwardly along the line 88 and pasted to the back of the pouring extension 72 as shown in Fig. 10. With this type of cup there is still less possibility of spillage over the sides of the pouring extension, by reason of the 55 tapered construction of the cup.

The cup of this invention may be readily manufactured in quantity at small expense, and may be readily opened for filling it with liquid. The trough-like pouring extension is relatively narrow and deep, so that the liquid is concentrated toward the center of the pouring extension, and spillage thereby prevented. Due to the fact that all the flaps are pasted onto the back of the pouring extension, the top of the pouring extension is 70 entirely smooth, and the pasted flaps are kept 75 out of contact with the fluid.

The cup may, if desired, be provided with 75 creases or folds, for facilitating the opening of the cup, although this is optional. The creases may be in the front of the cup, or in the back of the cup, or both, the convex part of the crease being outward. Referring to Figs. 1, 2, 3, and 11, the front of the cup is provided with a crease 90, and the back with a 80 crease 92; these creases extend longitudinally and centrally of the cup, from the pouring end back toward the other end of the cup, to about the middle of the cup, or a little beyond. As shown in Fig. 11, the edge or convex part 85 of each crease is outwardly extending. Due to the slight elasticity of the paper, the creases tend to push outwardly a small amount, thereby initiating the opening of the cup, the opening being completed by pressing together 90 the sides of the cup, as usual.

The other forms of the cup shown in Figs. 5-10, may, if desired, be provided with similar creases 90 and 92, as shown:

We claim as our invention:—

1. A foldable flat paper drinking cup having a tapered, trough-like pouring extension and a pair of flaps folded outwardly and backwardly and pasted to the outside, back part of the pouring extension, leaving the 105 pouring extension entirely smooth and unobstructed on its upper or pouring side.

2. A foldable flat paper drinking cup having a tapered, trough-like pouring extension and a pair of flaps folded outwardly and 110 backwardly and pasted to the outside, back part of the pouring extension, leaving the pouring extension entirely smooth and unobstructed on its upper or pouring side, the outer tip edge of the pouring extension being 115 also folded outwardly and backwardly and secured to the back of said pouring extension.

3. A foldable paper drinking cup comprising a tapered, trough-like pouring extension at one end, a pair of flaps bent outwardly and secured to the back of the pouring extension, the flaps being bent along converging lines whereby small triangular portions of the front of the cup are carried over onto the back of the cup.

4. A foldable paper drinking cup comprising a tapered, trough-like pouring extension having a pair of flaps folded into overlapping relation onto the back of said extension and secured thereto, leaving the pouring face 130

of the extension entirely smooth, the flaps being folded along converging lines whereby small substantially triangular portions of the front of the cup are carried around with said flaps to the back of the pouring extension.

5. A foldable paper drinking cup comprising a tapered, trough-like pouring extension, a pair of flaps folded outwardly and backwardly and secured to the back of said pouring extension, the flaps being folded along converging lines whereby small substantially triangular portions of the front of the cup are carried around to the back of the pouring extension, the extreme edge of the pouring extension being also bent around and secured to the back thereof.

10. A foldable paper drinking cup comprising a tapered, trough-like pouring extension, the sides of the cup converging toward the 20 pouring extension, the pouring extension having a pair of flaps bent outwardly and backwardly and pasted on the back thereof, whereby small substantially triangular portions from the front of the cup are carried 25 around to the back of the cup.

In testimony whereof we affix our signatures.

PHILIP A. FISCHER.
